WINDOW CONSTRUCTION

Michael Lochner, Buffalo, N. Y.

Application April 26, 1932. Serial No. 607,566

2 Claims. (Cl. 20—52.1)

This invention relates to certain new and useful improvements in window construction and particularly to the sash arrangement thereof.

One of its objects is to provide a window frame and sash construction which is simple, compact and inexpensive, and which embodies one movable sash designed and arranged to afford the advantages of the customary two-sash window construction.

10 Another object of the invention is the provision of a window construction which has been primarily designed for moderate priced homes, and which is constructed and arranged to permit the complete opening of the movable sash 15 above the window frame and within the room in which it is located.

20 A further object is to provide a window sash which can be easily removed from the frame when desired without disturbing any of the customary facing or trim elements thereof.

In the accompanying drawing:—Figure 1 is an inside elevation, partly in section, of a window frame and sash construction embodying my invention. Figure 2 is a vertical transverse section thereof taken on line 2—2, Figure 1. Figure 3 is a horizontal section taken on line 3—3, Figure 1. Figure 4 is a fragmentary view, similar to Figure 3, showing the manner of effecting the removal of the sash.

30 Similar characters of reference indicate corresponding parts throughout the several views.

Referring now to the drawing, the window frame preferably consists of upright sides or jam pieces 10 connected at their upper ends by a top piece or lintel 11 and at their lower ends by a sill 12. The inner and outer faces of this frame may be provided with the usual finishing or trim strips 13 and 14, respectively. As shown in Figures 2 and 3, this frame is so disposed relatively 40 to the wall 15 within which it is mounted that it projects somewhat into the room in which it is mounted, and as seen in those figures, the lintel 11 and sill 12 of the frame project inwardly beyond the plane of said wall.

45 Applied to the window frame is a sliding lower sash 16 and an upper fixed or stationary sash 17, the lower sash being preferably of a greater height than the upper one and in practice is such that, when the movable sash is raised, sufficient head room is afforded between the top of the frame and the ceiling to accommodate it in its fully raised position and to provide a window-opening of approximately the height of an average person. The lower sash 16 is disposed 55 within the inwardly-projecting portion of the

window frame and is guided at its side edges in suitable upright ways or grooves 18 formed in the jamb pieces 10 of the frame and located in a plane disposed inwardly of the room wall 15. These grooves extend through the top of the 60 frame and the lintel 11 terminates at its inner edge at the outermost edge of the grooves in the manner shown in Figure 2, whereby the lower sash 16 can be opened the full length of the 65 guide grooves and in the open position overlie the 70 adjoining wall of the room, as seen by dotted lines in Figure 2. These guide grooves for the lower sash are preferably formed by a division strip 19 applied to the side pieces of the frame between the contiguous faces of the upper and lower sash, 75 and by the upright trim pieces 13 which project inwardly or overhang the corresponding inside faces of the upright frame pieces 10, as shown in Figure 3. If desired, a stop strip 20 is applied to the side pieces of the frame and abuts against 80 the outer sides of the stationary sash 17.

The lower sash may be provided with the customary counterpoise weights 21 for holding it in its raised or elevated position. These weights are disposed in the plane of the lower sash and 85 inwardly of the room wall 15, a suitable compartment 22 being provided for housing them. By this arrangement, should the customary cord connecting the sash with the weight become broken, the sash-weight will merely drop to the 90 bottom of the compartment 22 or on to the sill 12 which is readily accessible by merely removing the upright inside finishing strip 13 which constitutes the inside wall of such compartment.

For the purpose of facilitating the removal of 95 the lower sash 16 when desired, I provide the bottoms of the guide grooves 18 with detachable longitudinal strips 23 against the faces of which the opposing side edges of the window normally ride. Adjacent their lower ends, these strips are 100 provided with suitable finger-engaging holes 24 for conveniently effecting their removal. By this construction, when it is desired to remove the sash from the frame, the same is raised to a suitable height sufficient to enable one to grasp the finger holes 24 of the strips 23, whereupon the latter are removed by a combined springing and downwardly pulling action. With the strips thus removed, the sash can be shifted bodily to 105 one side or the other of the frame opening and in this position the opposite edge of the sash will clear the adjoining edge of the upright trim strip 13, as seen by full lines in Figure 4, and enable the sash to be pulled inwardly and completely 110

removed from the frame in the manner shown by dotted lines in said figure.

I claim as my invention:—

1. In a window construction, a frame adapted for installation in a building-wall and having its jamb pieces, sill and lintel projecting inwardly from said wall, the jamb pieces having upright guide grooves therein opening through said lintel and disposed in a plane inwardly of the building-
wall, and a sash engaging said guide grooves and projectable above said frame in overlying relation to the room-wall.

2. In a window construction, a frame adapted for installation in a building-wall and having its jamb pieces, sill and lintel projecting inwardly from said wall, the jamb pieces having upright guide grooves therein disposed in a plane inwardly of the building-wall and opening through the top of the frame alongside said wall, a lower sash engaging said guide grooves and projectable above said frame alongside the room-wall and an upper sash fitted in the upper part of the frame and within the plane of said wall.

MICHAEL LOCHNER.
